UNITED STATES PATENT OFFICE.

RALPH CONWELL, OF BIG PINEY, WYOMING.

CORK-EXTRACTOR.

1,274,008.

Specification of Letters Patent. Patented July 30, 1918.

Application filed April 19, 1918. Serial No. 229,571.

To all whom it may concern:

Be it known that I, RALPH CONWELL, a citizen of the United States, residing at Big Piney, in the county of Uinta, State of Wyoming, have invented a new and useful Cork-Extractor; and I do hereby declare the following to be a full, clear, and exact description of the invention, such as will enable others skilled in the art to which it appertains to make and use the same.

This invention relates to an improved cork extractor, and one of the objects of the invention is to provide a simple, efficient and practical device of this kind comprising improved features of construction.

One of the features of construction consists in the provision of a pair of members pivotally united and having cork extracting jaws to be brought together to be forced into the cork, and then separated, so as to provide anchoring means to extract the cork.

A further object of the invention is to cork extracting jaws, so as to limit the jaws with means to interengage with the members to limit the outward movement of the members.

A further object of the invention is the provision of lips integral with the opposing cork extracting jaws, so as to limit the jaws in their closing action.

In practical fields the details of construction may necessitate alterations falling within the scope of what is claimed.

The invention comprises further features and combination of parts as hereinafter set forth, shown in the drawings and claimed.

In the drawings:—

Figure 1 is a view in section of the mouth end of a bottle and the cork therein, showing the application of the cork extractor.

Fig. 2 is a perspective view of the cork extractor.

Fig. 3 is an edge view of the cork extractor, showing its cork extracting jaws fitted in a leather shield.

Fig. 4 is a detail perspective view of the leather shield.

Referring more especially to the drawing 1 and 2 designate a pair of members. Each member is constructed from a single length of steel wire or any other suitable material, having one end portion flattened out and drawn to a point and the other end portion is turned to form a loop 4. The flattened portions of both members are pivotally united as shown, by means of the rivet 3.

The flattened part of both members extend at obtuse angles to the bodies of the members, so that when the members are separated the sharpened flattened extremities (which 60 constitute cork extracting jaws 6) may be brought together, as shown in full lines in Fig. 1, so as to pierce the center of the cork. It is to be noted that when the members are brought together, that is their handle ends, 65 the cork extracting jaws will be separated, as shown in dotted lines in Fig. 1, thereby providing anchoring means for extracting the cork. The cork extracting jaws on their edges remote from each other are provided 70 with oppositely and outwardly extending lips 7, which act as abutments to be engaged by the opposite edges of the jaws to limit the cork extracting jaws in their closing action. The finger engaging loops of the 75 members have their extremities 5 offset laterally in opposite directions, so that one of said ends 5 may be engaged by one edge of the member 2, and the other extremity engaged by one edge of the member 1, so as to limit the members, that is their handle ends in their closing action, as shown in dotted lines in Fig. 1, and as shown in Fig. 2 in full lines. When the cork extracting jaws are closed as shown in Fig. 3 they are inserted in a leather shield 8, a detail view of which is illustrated in Fig. 4. By means of this shield the sharpened ends of the jaws 6 are protected. This shield is constructed of two pieces of leather or other suitable material stitched together as shown.

The invention having been set forth what is claimed as new and useful is:—

1. In a cork extractor, a pair of members pivotally united, said members having cork extracting jaws adapted to be separated subsequently to having been inserted in a cork, said jaws having outwardly and laterally extending lips on their outer opposite edges, to be engaged by the other edges of the jaws, to limit the jaws in their closing actions, said members having loop handles having their ends disposed to provide means against which the handle members may abut to limit the handle parts of the members in their 100 closing actions.

2. In a cork extractor, a pair of members pivotally united, each member being constructed from a single length of steel wire material, said steel wire members adjacent 110 where they are pivotally united being flattened and drawn to points, thereby provid-

ing cork extracting jaws, said jaws having outwardly and laterally extending lips on their outer edges against which the other edges of the jaws contact to limit the jaws in their closing actions, the other ends of the members being extended and curved to form handle loops, having their extremities offset laterally in opposite directions providing abutment means against which the handle members contact to limit the handle members in their closing actions, the cork extracting

jaws extending at obtuse angles to the shanks of the handle members whereby the jaws may separate when the handle members are closed. 15

In testimony whereof I have signed my name to this specification in the presence of two subscribing witnesses.

RALPH CONWELL.
